Attorney.

UNITED STATES PATENT OFFICE.

WILLIAM J. McCAIG, OF BUFFALO, NEW YORK, ASSIGNOR TO THE REPUBLIC METAL-WARE COMPANY, OF BUFFALO, NEW YORK, A CORPORATION OF NEW YORK.

DESIGN FOR A VENTILATING FAN.

Application filed August 17, 1928. Serial No. 27,872 Term of patent 3½ years.

To all whom it may concern:

Be it known that I, WILLIAM J. McCAIG, a citizen of the United States, residing at Buffalo, in the county of Erie and State of New York, have invented a new, original, and ornamental Design for a Ventilating Fan, of which the following is a specification, reference being had to the accompanying drawings forming a part thereof.

The accompanying drawings:—Figure 1 is a side elevation of a ventilating fan of my new design. Figure 2 is a top plan view thereof.

I claim:

The ornamental design for a ventilating fan, substantially as shown.

WILLIAM J. McCAIG.
